UNITED STATES PATENT OFFICE.

DONALD B. SWAIN, OF MILLERS FALLS, MASSACHUSETTS, ASSIGNOR TO MILLERS FALLS COMPANY, OF MILLERS FALLS, MASSACHUSETTS, A CORPORATION OF MASSACHUSETTS.

LOCKING DEVICE AND TOOL.

Application filed July 11, 1923. Serial No. 650,830.

To all whom it may concern:

Be it known that I, DONALD B. SWAIN, a citizen of the United States, residing at Millers Falls, in the county of Franklin and State of Massachusetts, have invented certain new and useful Improvements in Locking Devices and Tools, of which the following is a full, clear, and exact description, such as will enable others skilled in the art 10 to which it appertains to make and use the same.

This invention relates to a locking device and tool which are preferably employed in combination.

15 It is an object of the present invention to provide an improved locking device which may be utilized in numerous different applications where two elements are movable with respect to each other, and where it is desired 20 that these elements may be locked to prevent movements in certain directions.

It is a further object of the present invention to construct a device of the character stated, in combination with a tool of the 25 twist type, whereby the spindle of this tool may be restrained against movement in certain directions with respect to the body thereof.

30 A still further object is that of furnishing a locking device which may be readily operated and wherein the operation of the movable elements is properly controlled.

Another object of this invention is to provide in connection with a tool embracing a 35 stock housing a spindle, these elements being adapted to be moved in opposite directions to impart a rotary motion to the spindle, a mechanism for preventing this movement when it is desired to utilize the tool for certain purposes, this mechanism being positive 40 in operation.

Still another object of the invention is that of furnishing a locking device and certain features of a tool of the character described, either of which is capable of independent use but which have particular utility when associated together.

45 Other objects of the invention will in part be obvious and will in part appear herein-after.

The invention accordingly comprises the features of construction, combinations of elements, and arrangement of parts, which will be exemplified in the constructions

hereinafter set forth and the scope of the 55 application of which will be indicated in the claims.

For a fuller understanding of the nature and objects of the invention reference should be had to the following detailed description 60 taken in connection with the accompanying drawing, in which:—

Fig. 1 is a fragmentary partly sectional side elevation of a tool embodying the improved construction of the invention, and 65 showing a locking device in association therewith;

Fig. 2 is an enlarged sectional side view 70 of the essential parts of the device as shown in Fig. 1 but illustrating these parts in a locked position;

Figs. 3 and 4 are views of the locking device with the covering plate removed and illustrating the same as applied to the 75 spindle of the tool, these views showing the position which the parts assume in unlocked and locked positions respectively; and

Fig. 5 illustrates the elements of the locking device in disassembled relation.

In the present embodiment of the invention and referring to Figs. 1 and 2, it will be seen that a tool has been shown such as is commonly used for the purpose of driving home and withdrawing screws, as well as for drilling. This tool embraces a stock including a handle 10 of any desired type, to which one end of a tube 11 is firmly attached, the opposite end of this tube being secured, in any desirable manner, to a frame 12. Disposed within the tube 11, and slideable with respect to the same, is a spindle 13, which is formed throughout a portion of its length with opposed spiral grooves 14, and attached to the inner end of this spindle is a collar 15, which slidably contacts with the inner face of the tube 11 and serves to retain the spindle properly supported therein.

A knurled sleeve 16 rotatably encircles the tube, and a ratchet mechanism is connected with this sleeve so that by turning the latter to one of two extreme positions, either the left-hand or right-hand spiral groove 14 will be engaged by the mechanism aforementioned. Also, this mechanism may be of such a nature that upon the sleeve being 105 moved to a position intermediate of the two extremes aforementioned, the spindle 13 will be held against rotation in either direction

upon an attempt being made to move the handle towards the outer end of the spindle. Thus, it will be understood that upon the sleeve 16 being moved to one of its extreme positions for the purpose aforementioned, moving the handle 10 towards the outer end of the spindle will result in the latter being rotated in one direction with respect to the handle; a setting of the sleeve 16 in its other extreme position and a similar movement of the handle towards the outer end of the spindle will cause the latter to be rotated with respect to the handle in an opposite direction, and finally if the sleeve is moved to its intermediate position and it being attempted to move the handle toward the outer end of the spindle, it will be found that the parts are locked with respect to each other and that no rotation results. Thus, assuming that a screw bit 17 is firmly attached to the spindle 13 by means of a suitable chuck 18, it will be appreciated that by manipulating the parts in the manner afore-described, and by previously introducing the bit into the groove of a screw head, that the latter will either be driven home or withdrawn. Also, by moving the sleeve in the last named position, i. e., an intermediate one, the tool may be used as an ordinary screw-driver or for any other purpose, according to the type of bit which is associated with the same. A mechanism of this type is well-known and may specifically be of that type shown in the patents to Furbish, #819,536, and Pratt, #887,423, or may be of any other suitable specific type best adapted for achieving the functions desired.

It will further be noted that that portion of the spindle 13, which lies adjacent to the frame 12 and extends beyond the same, is reduced as has been indicated at 19, so that a shoulder 20 is provided, which shoulder lies at the outer end of the spiral grooves 14, and when the spindle is fully retracted occupies a position substantially adjacent the outer end of the frame 12, the purpose of this construction being hereinafter brought out.

Applied to the outer edge of the frame 12 is a locking device, which in the present instance embraces a nut 21, which acts as a base and is attached to the frame by screw threads. Positioned adjacent the outer face of this nut are a pair of ring shaped cams numbered 22 and 23 respectively, these cams being so disposed with respect to each other that in one position the opening 24 of the inside cam is concentric with the outer edge of the outside cam 22. Finally it will be noted that the locking device embraces a cam housing 25, which has its inner edge inturned to slidably contact with the frame nut adjacent the edge of the latter, and a cam retainer 26 is attached adjacent the opposite edge of the housing 25 and serves to prevent

any accidental removal of the cams from within the same.

Now with a view of obtaining proper co-operation between the parts, it will be seen that the housing 25 carries an inwardly extending pin 27, which rides within a peripheral slot 28 formed in the edge of the frame nut 21, so that the movements of the housing with respect to this member are limited. The nut is also formed in its outer face with a transversely extending groove 29, and after the nut and housing are placed in proper position with respect to each other, the outside lock cam 22 is brought to bear against the face of the nut, it being noted that this cam is formed with a notch 30 in its edge, which notch straddles the pin 27 of the housing 25. Finally, the cam 23 is disposed within the opening of the cam 22, and this cam 23 carries a pin 31 which extends inwardly and rides within the groove 29 of the frame nut.

After the parts have been assembled in the relation aforementioned and the cover 26 has been applied in the manner shown in Fig. 2, it will be obvious, assuming that they are in the position shown in Fig. 2, that by turning the housing 25 with respect to the nut 21, this housing will carry with it the cam 22, while the cam 23 will not turn, incident to the engagement afforded between its body and the nut 21 by means of the pin 31 and the groove 29. Due to this action on the part of the cam 22, the cam 23 will move to a position at which its opening 24 will be eccentrically disposed with respect to the peripheral edge of the cam 22, nut 21 and housing 25. Thus, the parts will be caused to assume the position shown in Fig. 4, and if it is desired to return the same to the position which they previously occupied, this may readily be accomplished by simply turning the housing 25 and nut 21 in opposed direction with respect to each other. Due to this action, the pin 27 will engage the notch 30 of the cam 22 to turn the latter with respect to the nut 21, so that the cam 23 will be caused to have its pin 31 ride within the groove 29, thus resulting in its opening 24 again assuming a position at which it will be concentric with the peripheral edges of the cam 22, nut 21 and housing 25, it being noted that in this position this opening will be in registration with the openings of the nut 21 and the housing 25, as well as the bore of the tube 11.

Assuming that the tool afore-described is utilized in association with the locking device, as has been shown in the drawings of the present application, it will be understood that the same may normally be operated for drilling or other purposes by simply attaching any desired tool to the spindle 13, by means of the chuck 18 and properly manipulating the sleeve 16. If, it is desired that

the tool be employed as a ratchet screw-driver or drill, this may readily be accomplished by simply setting the sleeve 16, so that the spindle will have a lost motion in 5 one direction and be positively turned in the other direction. After the parts are thus set, the actuating member of the locking device, i. e., the housing 25, is rotated with respect to the base or nut 21 to cause the 10 locking dog, provided by the cam 23, to move towards the reduced portion 19 of the spindle and adjacent the shoulder 20, thus locking the spindle against outward movement with respect to the stock.

15 In order to prevent any inward movement of the spindle with respect to the tube, it will be noted, reference being had to Figs. 1 and 2, that the length of the spindle from its shoulder to its inner end is substantially 20 equal to the distance between the inner face of the cam 23 and a cap 32 which closes the inner end of the tube. Thus, with the parts in the position shown in Fig. 2, movement 25 of the spindle in either an inward or outward direction with respect to the tube 11 is prevented, first due to the fact that the opening of the locking device is constricted so that a portion of the body of the locking dog intersects the path of travel of the spindle and 30 more particularly the shoulder thereof, and secondly by the inner end of the spindle being in contact with the cap 32 which forms a fixed part of the tube 11. However, rotation of the parts with respect to each other 35 is not prevented, and thus simply by the use of mechanism of the proper type connected with the setting sleeve 16 a positive motion of the bit carried by the chuck may be secured in one direction when the handle 40 is twisted, while a lost motion occurs between these parts when the handle is turned in an opposite direction, it being understood that the sleeve may be turned to an intermediate 45 position to lock against movement in either direction.

From the foregoing it will be understood that the invention embraces a tool as well as a locking device, the former being capable of use in numerous connections in that by 50 means of the ratchet mechanism a movement longitudinally of the handle with respect to the spindle will cause the latter to be rotated. Also when the locking device is employed so that the tool acts as a ratchet screw-driver, or drill, the same ratchet mechanism as that 55 before mentioned, serves to produce the results desired so that all unnecessary complication is avoided aside from the fact that it is possible by this expedient to economically manufacture the tool. Furthermore, due to the fact that the contact edge of the innermost cam is angularly disposed with respect to the spiral grooves, no jamming of the 60 parts can be effected due to an accidental manipulation of the locking device during

the normal operation of the tool, it being seen that any jamming tendency is also precluded for the reason that it might be said that the contact edge of the cam is of greater width than the width of the grooves incident 70 to the angular disposition of the parts aforementioned.

Thus a locking device is provided the construction of which may be modified to meet various conditions, and this locking device 75 is of particular value when employed, for example, in connection with a tool of the type illustrated. It is obvious that this mechanism will be capable of utilization in most instances where it is desired at times to prevent the longitudinal movement of certain elements relatively to each other.

Since certain changes may be made in the above construction, and different embodiments of the invention could be made without departing from the scope thereof, it is intended that all matter contained in the above description or shown in the accompanying drawing shall be interpreted as 80 illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a locking device, in combination, a housing formed with an opening, a pair of ring-shaped cams arranged one within the other and one of the cams being rotatable with respect to the other whereby upon the occurrence of said rotation the innermost cam will be transversely moved, said cams being disposed adjacent said housing, and the central opening of the innermost cam being commensurate with the housing opening and concentric therewith when said innermost cam is in one position, and means to rotate one of said cams relatively to the other.

2. In a locking device, in combination, a holding member formed with an opening adapted to receive a spindle, a plurality of ring-shaped cams arranged one within the other, and one of the cams being rotatable relatively to the other whereby to cause a transverse movement of the innermost cam, said cams being disposed adjacent said holding member, the central opening of the innermost cam accommodating the movements of said spindle, and means for moving said cams relatively to each other to restrain certain movements of said spindle.

3. In combination, a spindle, a casing therefor, said casing being formed with an opening at one end to permit withdrawal of

the spindle, a cam member arranged adjacent said casing end and formed with an opening therein, means to mount the cam in position on the casing with the openings in said members in alignment, said cam being movable across the path of withdrawal of said spindle and said means comprising a member arranged for rotation with reference to the casing, and upon such rotation 10 causing a transverse movement of said cam member across the path of withdrawal of said spindle whereby the withdrawal of said spindle is prevented.

4. In a device of the character described, 15 in combination, a spindle formed with a shoulder, a cam formed with an opening therein of sufficient size to permit the movement of said shoulder therethrough when the cam and spindle are in certain relative 20 positions, means normally to maintain the cam and the spindle in said relative positions, and means to alter the relative positions of the cam and the spindle to prevent movement of the shoulder through the 25 opening of the cam.

5. In a locking device, in combination, a pair of relatively rotatable members, one of said members being formed with a central opening, a cam member formed with an 30 opening normally aligned with the aforesaid opening and arranged for movement to an operative locking position in response to the rotation of one of said rotatable members with reference to the other in a direction transverse to the axis of rotation, means 35 to limit the relative rotation of said rotatable members in one direction when the cam is in normal inoperative position, and means to limit the relative rotation thereof in the 40 other direction when the cam is in a transversely fully extended position.

6. In a device of the character described, 45 a spindle having a reduced portion, a ring-shaped cam encircling said reduced portion, the inner radius of the cam and the radius of the spindle being such as to permit of the longitudinal movement of said spindle through the opening in said cam when the center of said opening is in alignment with 50 the axis of said spindle, means to support said cam and said spindle, means carried by said supporting means to move the cam to a position wherein the movement of the spindle through the opening in the cam is 55 prevented, and means to limit the movement

of said cam before it enters into locking engagement with said spindle.

7. A locking device, including a pair of ring-shaped cams arranged one within the other so that the rotation of either of said cams will cause a transverse movement of the innermost cam, a ring-shaped support for said cams formed with a transverse groove, the inner radii of the support and the innermost cam extending normally from a common axis and being substantially equal, means for causing relative rotary movement of one of said cams with reference to the other and a pin associated with one of said cams and extending into the groove in said support to guide said cam during the operation of said means so as to constrict the size of the opening through said innermost cam and said support. 60 65 70

8. In a locking device, in combination, a pair of ring-shaped cams arranged one within the other with their cam faces in engagement so that the rotation of one of the cams will cause a transverse movement of the other, a ring-shaped support for said cams, a housing enclosing said cams, said support and said housing being mounted for relative rotary movement and said support being formed with a peripheral slot terminating at either end in shoulders on 80 85 said support, a pin carried by said housing and extending into said slot, the shoulders on said support being adapted to cooperate with said pin to limit the relative movements of the support and the housing, the outermost of said cams being formed with a notch adapted to cooperate with said pin to prevent relative movement of the housing and the outermost cam, and means to prevent rotation of said support and the innermost cam one with the other. 90 95

9. In a locking device, in combination, a pair of ring-shaped cams arranged one within the other with their cam faces in engagement so that the rotation of the outermost cam will cause a transverse movement of the innermost cam, a support for said cams, said support being formed with a transverse groove, a pin carried by said innermost cam and extending into said groove, and means to rotate said outermost cam. 100 105

In testimony whereof I affix my signature.

DONALD B. SWAIN.
